CLAIM

The ornamental design for a rolled material dispenser lockout, as shown and described.

DESCRIPTION

FIG. 1 is an isometric view of a rolled material dispenser lockout according to our new design viewed from in front of, above, and from the right side thereof;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof;

FIG. 7 is a left side elevation view thereof;

FIG. 8 is an isometric view of another embodiment of the rolled material dispenser lockout of FIGS. 1-7, viewed from in front of, above, and from the right side thereof;

FIG. 9 is a front elevation view thereof;

FIG. 10 is a rear elevation view thereof;

FIG. 11 is a top plan view thereof;

FIG. 12 is a bottom plan view thereof;

FIG. 13 is a right side elevation view thereof;

FIG. 14 is a left side elevation view thereof;

FIG. 15 is an isometric view of another embodiment of the rolled material dispenser lockout of FIGS. 1-14, viewed from in front of, above, and from the right side thereof;

FIG. 16 is a front elevation view thereof;

FIG. 17 is a rear elevation view thereof;

FIG. 18 is a top plan view thereof;

FIG. 19 is a bottom plan view thereof;

FIG. 20 is a right side elevation view thereof; and,

FIG. 21 is a left side elevation view thereof.

The evenly spaced broken lines are for illustrative purposes and show portions of the article and environment; the dot dash broken lines show boundaries of the claimed design; all broken lines form no part of the claimed design.
